UNITED STATES PATENT OFFICE

BERT A. BIRDSALL, OF DECATUR, NEBRASKA, ASSIGNOR OF ONE-HALF TO HENRY C. KING, OF DECATUR, NEBRASKA

SPARK PLUG

Application filed April 2, 1929. Serial No. 351,958.

This invention relates to improvements in spark plugs, particularly spark plugs designed for use in internal combustion engines.

The primary object of this invention is to provide a spark plug so designed and constructed that fouling thereof will not take place.

Another object of the invention is to provide an improved type of spark plug so constructed that an intensifying of the current will take place through the provision of gaps across which a firing current must jump, means being provided whereby one of said gaps may be adjusted.

Still another object of the invention is to provide an improved spark plug so designed that the expanding and contracting action of the metal of the electrodes, when the same become hot, will not change the spark gaps to weaken the spark produced.

Other objects and advantages of the invention will become apparent as the description of the same proceeds and the invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications mark no material departure from the salient features of the invention as expressed in the appended claim.

In the drawings:—

Figure 1 is a central longitudinal sectional view of the spark plug embodying the present invention;

Figure 2 is an elevational view of the lower end of the plug.

Referring to the drawings in detail wherein like numerals of reference indicate corresponding parts throughout the several views, the numeral 1 indicates the porcelain body of the present spark plug, which body as shown, is relatively long and is circumferentially enlarged adjacent the lower end, as indicated at 2, and between the enlargement 2 and the adjacent end is of tapered formation, as indicated at 3.

In the upper end of the body 1 a recess or pocket 4 is formed and adjacent the pocket the body is provided with the surrounding groove 5 in which the edge of a metal cap 6 is forced when the cap is placed in position over the top end of the insulation body in the manner shown. The top portion 7 of the cap 6 is provided with a threaded aperture 8 which opens into the recess 4, and this threaded aperture has extended therethrough the electrode screw 9, the upper end of which has a kerf 10 formed transversely thereof for the reception of a screw driver when the spark gap, hereinafter described, located in the recess 4, is to be adjusted.

Formed to receive the lower portion of the insulation body 1, is a cylindrical shell 11 of the usual type, the lower end of which is exteriorly threaded, as indicated at 12 for engagement in the cylinder head of an engine. Intermediate the ends of this shell the inner face of the wall is provided with a shoulder 13 to receive the lower edge of the enlarged portion 2 of the insulation body and surrounding the insulation body and threaded secured in the upper end of this shell is a binding nut 14 which bears at its lower edge against the upper side of the enlargement 2 to secure the insulation body in position.

As is shown, the tapered lower end of the insulation body 1 terminates above the lower end of the shell body 11 and the inner edge of the shell body is beveled as at 15, so the inner wall of the lower end of the shell flares outwardly, as shown.

Running longitudinally through the insulation body 1 is a main central electrode 16, the upper end of which extends into the recess 4 and is formed to provide the head 17 which is normally spaced from the lower end of the screw 9 to form a spark gap therewith. The lower end of the electrode 16 extends downwardly beyond the lower end of the insulation body 1, and secured in the lowered tapered end of the insulation body adjacent the electrode 16, is an auxiliary electrode 18. The space between the angled portion of the auxiliary plug 18 and the beveled face 15 of the shell is adjusted to give a spark of the best character and due to the re-

lation between the angled portion of the auxiliary electrode and the beveled portion of the shell this space will not vary with the expansion and contraction of the electrode.

5 The auxiliary electrode 18 in addition to being angularly extended from the lower end of the body 1, as shown and described, terminates in a transversely extending portion 19 which lies at right angles and in spaced relation to the main electrode 16.

10 The lower end of the insulation body 1 is formed between the electrodes 16 and 18 to provide a V-shaped ridge 20 which acts to prevent carbon from coating the lower end 15 of the insulation body and forming a short circuit between the two electrodes.

Having thus described my invention, what I claim is:—

20 A spark plug, comprising a shell having an inner edge at one end beveled, an insulation body secured in the shell with one end adjacent said beveled edge, a main electrode extending through said body and projecting straight from said end, and an auxiliary electrode 25 extending from said end of the body and having one portion angled to parallel the face of said bevel and a terminal portion extending transversely of and spaced from the adjacent straight portion of the main electrode.

30 In testimony whereof I hereunto affix my signature.

BERT A. BIRDSEALL.
